UNITED STATES PATENT OFFICE.

FRANK S. INGOLDSBY, OF PINE LAKE, AND HENRY T. GIBBARD, OF HIGHLAND PARK, MICHIGAN, ASSIGNEES TO THE INGOLDSBY AUTOMATIC CAR COMPANY, OF CLEVELAND, OHIO, A CORPORATION OF WEST VIRGINIA.

DUMP-CAR.

1,286,593.

Specification of Letters Patent.

Patented Dec. 3, 1918.

Application filed November 27, 1916. Serial No. 133,529.

To all whom it may concern:

Be it known that we, FRANK S. INGOLDSBY and HENRY T. GIBBARD, citizens of the United States, residing at Pine Lake and 5 Highland Park, respectively, in the counties of Oakland and Wayne, respectively, and State of Michigan, have invented a certain new and useful Improvement in Dump-Cars, of which the following is a full, clear, 10 and exact description, reference being had to the accompanying drawings.

Prior Patent No. 1,013,552 issued January 2, 1912, to The Ingoldsby Automatic Car Company, as assignee of Frank S. Ingoldsby, shows and claims a combined locking and raising mechanism for dump ears, so arranged that oscillations of a lever, which in final position locks the doors, may serve to raise them. The invention is 20 there shown as embodied in a car of the Ingoldsby type, wherein a load-supporting door has projecting floor beams which may be engaged by hooks on the sides of the car to hold it in closed position, the hooks on 25 the two sides being operated by two levers respectively. To raise the doors a longitudinal bodily-movable bar is provided on each side, which is connected by flexible members with the door and has teeth which may be 30 engaged by a pawl carried by an extension of the main locking lever. A suitable detent pawl is also provided, which may engage these teeth. Thus oscillations of the main lever may serve to gradually move the 35 longitudinal bar and pull up on the flexible members to close the door.

The present invention is in the nature of an improvement on the structure shown in the prior patent referred to, and is also in 40 some ways an improvement on the structure shown in application #125,787, of Frank S. Ingoldsby, filed October 16, 1916. The present invention includes a very simple and effective automatic release for the pawls, 45 when the doors are finally locked, to insure the pawls being out of engagement with the longitudinally-movable bar when the doors are locked. This mechanism includes also an effective form for these pawls. Another 50 feature of the invention is a very compact and satisfactory system of guides for the chains between the longitudinal bar and the door, including the nesting of one chain guiding pulley within the flanges of the

other guiding pulley, which also supports 55 the bar, and including also an effective form of guard and guide which reinforces the lower chord where the chain passes through it, and guides the chain as it bends from the vertical to a diagonal direction when the 60 door drops. These features will be herein-after more fully explained, and the essential characteristics summarized in the claims.

In the drawings, Figure 1 is a side elevation of a portion of a car embodying our invention; Fig. 2 is a transverse section of a portion of such car; Fig. 3 is an enlarged transverse sectional view on the line 3—3 of Fig. 1; Fig. 4 is a sectional end view of 65 a portion of the car, showing the pawl releasing mechanism; Fig. 5 is a fragmentary plan of parts shown in Fig. 4; Fig. 6 is a 70 horizontal section through a portion of the ear side, just above the lower chord, illustrating the chain guide in dotted lines, the 75 hook attached to the side of the car being omitted for clearness of illustration. Fig. 7 is a vertical transverse section through a portion of the car side and door at the raising chain; Fig. 8 is a vertical section 80 through the raising bar and the supporting and chain guiding pulley; Fig. 9 is a transverse section on a horizontal plane through the supporting and chain guiding pulley; Fig. 10 is a plan of a portion of the operating 85 bar and chain where they pass through the stiffener; Fig. 11 is a perspective of the operating parts of the rack and pawl mechanism shown in Fig. 1.

We will first describe the general construction and operation of the device and then take up the particular features with which this invention is concerned.

In the drawings, 12 represents the side 90 of a car which is shown with a plate girder 13, having an upper chord 13, a lower chord 14, and side stiffeners 18. 20 designates a central longitudinal ridge member, and 22 inclined end floors. The dumping doors, designated 25, are shown as hinged on longitudinal axes 26, at the lower edge of the center ridge 20. It is to be understood that the division of the car into hoppers, the arrangement of the doors, and the direction of their hinged axes, may be changed as 100 105 desired.

Pivoted to the sides of the car are hooks or levers 30 the lower ends of which are

adapted to engage beneath the projecting ends of the floor beams 27. Each of these hinged levers is pivoted near its lower end as illustrated at 31, and extends through a 5 longitudinal slot 15 (Fig. 6), in the lower chord. The hook portion may conveniently be beveled at its engaging edge 32, and the projecting ends of the floor beams may be hooked in a plane parallel with the door, as 10 illustrated at 33, so that the side hooks and the floor beam hooks interlock with each other and serve to pull the doors snugly up against the lower chord 16 and at the same time hold the side of the car against outward bulging.

To hold the hooking levers 30 in their locked position, as well as to release them as a unit, they are all pivoted at their upper ends to a longitudinal link 35 which is connected at its end to an intermediate link 36 pivoted to the main operating lever 40. This lever is shown as pivoted at 41 to the side of the car, which is suitably reinforced at this point. The movement of the lever 40 25 is limited by the guide iron 45, shown as extending alongside of the path of movement of the lever and secured at one end to the car side and at the other to an inclined end strut 47. 30 To raise the doors the bodily movable longitudinal bar 50 is provided, to which are anchored the upper ends of the chains 51, which extend over pulleys 52 and thence downwardly, passing through openings in 35 the lower chord and being secured at their lower ends to the doors. The longitudinal bar is provided with ratchet teeth 60 on its upper face, with which coacts a pawl 61 pivoted at 62 to a lower extension of the main 40 operating lever. A detent pawl 64 extends transversely of the end of the car and stands above the teeth 60 of the longitudinal bar and is adapted to engage them and hold the gain made by the feeding pawl 61.

45 In operating the mechanism so far described, if the doors are down the chains will have drawn the longitudinal bar toward the right, from the position shown in Fig. 1. Now oscillations of the main lever 50 40, by reason of the pawl 61 and the detent pawl 64, will move the longitudinal bar to the left, or toward the end of the car, thus drawing upon the chains and raising the door. The last forward movement of the 55 lever brings the door practically home, and the final backward movement swings the hooks 30 beneath the floor beams, whereby the doors are locked shut and the strain is taken off the raising mechanism.

60 We will now describe the arrangement of guides shown for each chain, connecting the operating bar with the door. As shown the operating bar consists of a pair of flat strips side by side and spaced apart but secured 65 rigidly to each other by suitable rivets 55

and distance pieces 56. The slot between the side members of this bar is sufficient to easily accommodate those links of the chain which stand vertically, whereas the horizontal links lie beneath and in contact with the bottom faces of the two strips. The guide pulley 52, over which the chain is shown as extending, has a peripheral groove 53 to receive the links presented edge-wise, and cylindrical surfaces 54, to receive the links presented flat-wise. Outside of these cylindrical surfaces the pulley has two extended peripheral flanges 57 which extend beyond the flat-wise links and overlap the sides of the bar 50. This pulley 52 supports 70 the bar, being positioned so that the highest point of its cylindrical surface is below the desired portion of the bar by an amount equal to the thickness of the chain.

To hold the chain effectively against the pulley 52 and also to support the chain if the upper end thereof is carried beyond the pulley 52, we provide the pulley 70, which has a peripheral groove 71 to receive the edge-wise links, and cylindrical surfaces 72 for 90 the flat-wise links, but has no flanges, this pulley being positioned to extend between the flanges 57 of the pulley 52. The peripheral grooves of the two pulleys, it will be seen, coact to effectively guide those links of the chain which lie in a plane parallel with the car side, while the cylindrical surfaces of the pulleys coact to guide the other links. The pulley 70 is positioned such distance below the bar that the space between its cylindrical surfaces and the bottom of the bar corresponds to the thickness of the chain links, and thus this pulley may support the chain and bar if momentum carries the upper end of the chain across the pulley 70. If the bar and chain pass through a stiffener 18, as illustrated in Figs. 1 and 10, the stiffener may be reinforced by an additional strip 19, riveted to it, as shown.

To effectively secure the pulleys 52 and 70 to the car side, without causing undue projection thereat, we provide studs 80 and 81 (as shown in Fig. 9), which extend through a reinforcing bar 82 on the inner face of the car side 12, and thence outwardly through bearing sleeves 84 and 85, on which the pulleys 52 and 70 are mounted. These pulleys are provided in their outer faces, with recesses 58 and 74 respectively, and in these recesses are fastening devices on the 110 studs 80 and 81, the fastening devices shown comprising washers 86 and 87 overhanging the respective pulleys, and nuts 88 and 89, screwed onto the studs and clamping the washers against the ends of the bearing sleeves. The construction described makes a very effective, firm and compact guiding and supporting device for the chain and the bar.

The chain 51 depends vertically from the 130

space between the supporting and guiding pulleys, and passes through the lower chord and is anchored at its lower end to the door. There is shown (Figs. 6 and 7), a round hole 16, through the lower chord, where the chain passes. The lowermost member of the chain is in the form of an eye 59, the shank of which passes through a member 28, and is secured thereto by a nut. These attaching members 28 are shown as secured to the lower side of the door and projecting from its edge.

To effectively guide the chain as it bends from the vertical to the diagonal position at the lower chord, when the door drops, we provide a stirrup 90, shown in Figs. 3, 6 and 7. This stirrup is a flat strip, the intermediate portion of which is twisted at something more than a right angle to the end portions, and is curved in two directions. That is to say, in horizontal planes the intermediate portion is concave, to lie around the inner portion of the round hole 16; in vertical planes the intermediate portion is convex on the outer face, to provide an efficient rub plate for the chain. This stirrup is secured to the lower chord, preferably by rivets 91, as shown in Fig. 6. This simple device reinforces the chord at the opening, 20 prevents wear at the inner edge of the opening, and provides an effective guide for the chain. It occupies small space beneath the chord and requires little recessing at the outer edge of the door 25.

We will now describe the particular arrangement of pawls shown for controlling the raising bar, and the device for throwing these pawls to idle position when the bar is finally locked, this construction being shown in Figs. 1, 4 and 5.

The pawl 64 is pivoted at 65, and thus has its outermost portion adapted to drop by gravity, into engagement with the teeth 60 of the longitudinal bar. The pawl 61 has a tail extending across the pawl 64 so that when the pawl 64 is raised to clear the teeth it automatically raises the pawl 61 out of engagement.

Now during the raising operation, the parts are as shown in Fig. 4, both pawls by gravity engaging the teeth. Accordingly, the oscillation of the lever 40 may gradually move the bar 50 toward the end of the car and raise the door. When the car is finally locked it is desirable to automatically maintain the pawls out of engagement with the teeth 60, so that no undue strain can be thrown on these parts when the doors are dropped. It is customary to provide In- 60 goldsby cars with a locking dog, illustrated at 100 in Figs. 1 and 4. This dog is pivoted to a bracket 101 on the end strut 47 and is adapted to be turned in front of the locking lever against a shoulder (which may be provided by the guide irons 45) when the

lever is in locked position. The dog has an extension 103 which we connect by a chain 105 with the pawl 64, between its pivot and its engaging face. Now when the dog is turned from the position shown in full lines in Fig. 4, to that shown in dotted lines, to lock the main lever, the chain 105 raises the pawl 64 into the position shown in dotted lines, where it clears the teeth of the bar 50. The pawl 64 engages the tail of the pawl 61, and raises it clear of the bar. Accordingly, the mere turn of the bar lock 100 into active position (which is always done as soon as the doors are raised and locked), automatically carries the pawls to idle position.

We also provide a gravity latch 110 pivotally mounted at the end of the car and adapted to swing by gravity over the top of the inner end 68 of the pawl 64, when the latter is raised to idle position. The active or engaged position of the pawl and the corresponding disengaged inactive position of the gravity latch are shown in full lines in Fig. 4. The inactive position of the pawl appears in dotted lines in this view, and dotted lines also show the gravity latch in the active position it then occupies to hold the pawl elevated. A suitable stop 111 limits the movement of the gravity latch. The engagement of the gravity latch at once relieves the bar lock 100 of any tendency to be pulled back from its locked position. It also holds the pawl in idle position when the bar lock is turned back by hand to release the load.

It results from the above described mechanism that as soon as the doors are raised and locked, and the locking lever itself locked, the pawls become automatically disengaged and the car is ready for dropping the doors whenever desired. When the doors are to be dropped the bar lock is turned back to the position shown in full lines, but the gravity latch retains the pawls in an elevated position, so that when the doors drop the bar 50 is carried freely forward. When it is desired to close the doors it is only necessary for the operator to kick out the gravity latch 110, allowing the weighted outer end of the pawl 64 to carry it downwardly into engagement with the teeth of the bar 50, this same movement allowing the feeding pawl 61 to drop into active position. Then the oscillations of the main lever operate to raise the door, as hereinafter explained.

Fig. 1 shows the pawl 61 formed in a special manner, with a series of curves. This pawl preferably rides over a laterally extending finger 123 rigid on the pawl 64, and this finger is accurately positioned by bending or turning to coact with the pawl 61 and cause it to engage or clear the teeth 60 at the proper time. The concavity 120 at 130

the under side of the pawl, adjacent to the tooth, is for the purpose of allowing proper clearance over the detent pawl finger on the extreme backward stroke of the feeding pawl. The convexity 121 at the rear of the concavity is to enable the detent pawl to properly support the feeding pawl out of active position when the car is locked, and while the main lever is traveling forward 10 to unlock the door and dump the load. The extreme extension 122 of the pawl is provided to give it sufficient gravity and still cause it to clear the rest of the mechanism.

In the particular form illustrated it is proposed to move the longitudinal bar by oscillations which feed it a maximum of two teeth at a time, and the teeth are so arranged that on the last maximum movement one-half of the travel of the feeding pawl is 20 idling while the levers 30 are moving out of the way, and as the latter continue to move still farther out of the way the feeding pawl moves the bar and thus raises the floor beams of the door from immediately below 25 to immediately above the end 32 of said levers 30, and this end 32 rotating on the axis 31 acts as a wedge to lift the door into a tight joint and at the same time release the strain on the chain, bar and pawl.

30 Having thus described our invention, what we claim is:

1. In a dump car, the combination with a dumping door, of door closing mechanism including a pawl tending to move to active 35 position, door locking mechanism, means operated thereby for positively moving said pawl to idle position, and an automatic latch for holding it in idle position.

2. In a dump car, the combination of a 40 dumping door, door raising mechanism including an actuating device therefor, door locking mechanism, means whereby the locking of the door automatically and positively moves a part of the actuating device to disconnect it from the rest of the raising mechanism, part tending to return to engaging position, and a latch for holding said part disconnected.

3. In a dump car, the combination with 50 a dumping door, of door closing mechanism including a pawl tending to move to active position, door locking mechanism, means operated thereby for moving said pawl to idle position, and a latch for holding the 55 pawl in this idle position when the door is unlocked.

4. In a dump car, the combination of a 60 dumping door, raising mechanism therefor including a gravity pawl, door locking mechanism including a movable lock, connecting mechanism between said pawl and lock whereby the movement of the lock to active position raises the pawl to inactive position, and a latch for holding the raised pawl.

65 5. In a dump car, the combination of a

dumping door, door closing mechanism including a pawl tending to move to active position, hooks for holding the door closed, a main lever connected with said hooks, a movable locking dog for the main lever, 70 and connecting mechanism between the dog and the pawl.

6. In a dump car, the combination of a dumping door, door closing mechanism including a gravity pawl, hooks for holding 75 the door closed, a main lever connected with said hooks, a movable locking dog for the main lever, connecting mechanism between the dog and the pawl adapted to raise the pawl to idle position when the locking member is turned to active position, and a gravity latch for holding the pawl raised.

7. In a dump car, the combination of a dumping door, a longitudinally movable bar connected with the door, whereby 85 movement of the bar may raise the door, said bar having teeth, a pawl adapted to engage said teeth to hold the bar, a locking device for the closed door, and a connection between the same and said pawl whereby 90 the operation of the locking device may raise the pawl to inactive position, and a latch for the pawl when inactive.

8. In a dump car, the combination of a dumping door, a longitudinally movable 95 bar, a flexible connection between the bar and door, locking hooks and a main locking lever connected therewith for holding the door closed, a locking device for said lever, a pawl for holding the bar, connecting 100 mechanism between the locking device and pawl enabling the locking device when operated to automatically move the pawl to inactive position, and a latch for the pawl when in this position.

9. In a dump car, the combination with a dumping door, of door raising mechanism including a pawl having a tendency to assume active position, door locking mechanism, a locking device for the last mentioned mechanism, and a flexible connection between said device and the pawl whereby the movement of said device into locking position positively moves the pawl to inactive position.

10. In a dump car, the combination with a dumping door, of door raising mechanism including a gravity pawl tending to assume active position, door locking mechanism, a movable locking device for the last mentioned mechanism, and a flexible connection anchored at one end to said device and at the other end to the pawl, whereby the movement of said device into locking position raises the pawl to inactive position.

11. In a dump car, the combination with a dumping door, of door raising mechanism including a pawl having a gravity tendency to assume active position, door locking mechanism, a locking device for the last mentioned 130

mechanism, a flexible connection between said device and the pawl whereby the swinging of said device into locking position raises the pawl to inactive position, and a latch adapted to automatically engage and hold the pawl when moved to inactive position.

12. In a dump car, the combination with a dumping door, of door raising mechanism including a gravity pawl having a tendency to assume active position, door locking mechanism including a locking lever, a pivoted locking member for said lever, a flexible connection anchored at its ends to said locking member and pawls respectively, whereby the swinging of said member into locking position raises the pawl to inactive position, and a gravity latch adapted to automatically engage and hold the pawl when moved to inactive position.

13. In a dump car, the combination of a dumping door, door closing mechanism comprising a movable member and a flexible connection between the same and the door, and a pair of coacting pulleys between which said flexible connection passes, one of said pulleys having a peripheral flange overlapping the other pulley.

14. In a dump car, the combination of a dumping door, door closing mechanism comprising a longitudinally movable bar and a flexible connection between the same and the door, a pair of coacting pulleys between which said flexible connection passes, one of said pulleys having peripheral flanges and the other pulley extending between said flanges.

15. In a dump car, the combination of a dumping door, a movable bar, a chain connected to the door and bar, a pulley over which the chain passes and which is provided with a recess for the links presented edgewise and a supporting portion for the links presented flatwise, and a projecting flange, and coacting pulleys positioned to be overlapped by said flange and having a recess for the links presented edgewise and a supporting portion for the links presented flatwise.

16. In a dump car, the combination of a dumping door, a movable bar, a chain connected to the door and bar, a pulley over which the chain passes and which is provided with a peripheral groove for the links presented edgewise and a cylindrical portion for the links presented flatwise, and projecting flanges, and a coacting pulley extending between said flanges and having a peripheral groove for the links presented edgewise and a cylindrical portion for the links presented flatwise.

17. In a dump car, the combination with a dumping door, of a movable bar, a flexible member connected to the door and bar, a pulley located adjacent the bar and having

the flexible member passing across it, said pulley having a peripheral flange extending across the flexible member and overlapping the bar, and a coacting pulley which said flange also overlaps.

18. In a dump car, the combination with a dumping door, of a movable bar, a chain connected to the door and bar, a pulley located adjacent the bar and having the chain passing across it, said pulley having peripheral flanges extending across the chain and overlapping the bar on opposite sides, and a coacting pulley which extends between said flanges.

19. In a dump car, the combination with a dumping door, of a longitudinally movable bar, a chain anchored at one end to the bar and the other to the door, said chain extending for a distance along the under side of the bar, a guide pulley across which the chain then passes, said pulley having a peripheral groove to receive the links presented edgewise and having supporting portions to receive the links presented flatwise, the highest point of said portions being a distance below the bar substantially equal to the thickness of the chain, whereby the supporting portions may support both the chain and bar, and peripheral flanges on said pulley which extend across the chain and overlap the bar, and a guide pulley extending between said flanges and coacting with said chain.

20. In a dump car, the combination with a car side and a dumping door, of a pair of pulleys journaled on the car side, one of said pulleys having a pair of peripheral flanges and the other pulley extending into the space between said flanges, a movable bar guided on the side of the car and standing between the uppermost portions of said flanges, and a chain anchored to the bar and extending along its under side and passing between the flanges then through the guiding space between two pulleys and having its lower end connected to the door.

21. In a dump car, the combination with a dumping door, of a longitudinally movable bar having a vertical slot in it extending lengthwise thereof, a chain having its end link extending into said slot and there secured, said chain extending along the under side of the bar with the vertical links extending into the slot and the horizontal links engaging the lower edges of the bar, a pulley across which the chain then passes to the door, said pulley being recessed to receive the links presented edgewise and having a portion to support the links presented flatwise and having peripheral flanges extending beyond the flatwise links and overlapping the bar on its outer sides, and a co-operating pulley mounted on a parallel axis and extending into the space between the flanges.

22. In a dump car, the combination with a dumping door, of a movable bar, a flexible member connecting the bar with the door, a pulley across which the flexible member passes intermediately; said pulley having portions to support the portion of the flexible member and bar and having peripheral flanges overlapping the bar on both sides, and a coöperating pulley mounted on a parallel axis and extending into the space between the flanges, said coöperating pulley guiding the flexible member and having portions adapted to support it and the bar, the highest point of said supporting portions of the coöperating pulley being substantially the same distance below the bar as the supporting portions of the first mentioned pulley. 10
23. In a dump car, the combination with a dumping door, of a longitudinally movable bar having a vertical slot in it extending lengthwise thereof, a chain anchored to the bar and lying partly along the under side of the bar with the vertical links extending into the slot and the horizontal links engaging the lower edges of the bar, a pulley across which the chain then passes to the door, said pulley being recessed to receive the links presented edgewise and having a portion to support the links presented flatwise and having peripheral flanges extending beyond the flatwise links and overlapping the bar, and a coöperating pulley mounted on a parallel axis and extending into the space between the flanges, said coöperating pulley being recessed to receive the links presented edgewise and having a portion to coact with the links presented flatwise, the highest point of said supporting portion being substantially the same distance below the bar as the supporting portion of the first mentioned pulley. 20
24. In a dump car, the combination with a dumping door and car side, of a pair of pulleys, one provided with peripheral flanges and the other flangeless, the flangeless pulley extending between the flanges of the other pulley, a pair of outwardly extending parallel studs carried by the car side and forming bearings for the pulleys, one or both of said pulleys having a recess on its outer face occupied by a fastening device on the outer end of the stud, an operating device, and a flexible member connected therewith in passing between the pulleys to the door. 30
25. In a dump car, the combination with a car body, of a dumping door, a stud carried by the car body and projecting outwardly, a sleeve on said stud, a pulley journaled on said sleeve, said pulley having a recess in its outer face, a fastening device on the outer end of the stud clamping the bearing sleeve and overlapping the pulley in the recess, an operating device, and a flexible member connected therewith in passing over the pulley to the door. 40
26. In a dump car, the combination of a car side having a lower chord, a dumping door, a flexible member secured to the door near its swinging edge, and a stationary rub-plate for the flexible member secured to the lower chord. 70
27. In a dump car, the combination of a car side having an outstanding flange, a dumping door, a flexible member for closing the door extending through an opening in said flange and secured to the door, and a rub-plate secured on the under side of the flange and extending on the inner side of the opening. 75
28. In a dump car, the combination of a car side having a flange with an opening to it, a dumping door, a flexible raising member extending through said opening and secured to the door, and a combined reinforce for the flange and guide for the flexible member consisting of a strip secured to the flange and having its intermediate portion extending away from the flange, said intermediate portion of the strip being located immediately along the inner side of the space adjoining the opening through the flange. 80
29. In a dump car, the combination of a car side having a lower chord with an outstanding flange, a dumping door, a flexible member for raising the door extending through an opening in said flange and secured to the door, and a rub-plate formed of a strap of metal having its intermediate portion twisted at an angle with reference to the end portions, said end portions being secured to the under side of the chord and said intermediate portion lying on the inner side of the opening through the chord and forming a guide beneath said opening. 90
30. The combination of a car side having a lower chord with an outstanding flange, a dumping door, a chain extending through an opening in the outstanding flange and secured at its lower end to the door, and a guiding device for said chain comprising a strap of metal twisted intermediately with reference to the end portions and curved toward the chain concavely in horizontal planes and convexly in vertical planes, said strap having its end portions secured to the under side of said flange. 100
31. In a dumping car, the combination with a dumping door, of a longitudinally movable bar having a slot extending lengthwise thereof, a chain secured to the bar and to the door, a guide member across which the chain passes, said slot being adapted to receive links of the chain presented edgewise thereto while the adjacent edges of the bar engage the links presented crosswise. 110
32. In a dump car, the combination with a dumping door, of a longitudinally mov- 120
- 125
- 130

able bar having a vertical slot extending lengthwise thereof, a chain secured to the bar extending along the same and attached to the door, a pulley across which the chain 5 passes to the door, the pulley having a peripheral groove adapted to receive portions of links presented edgewise thereto, while the groove in the bar receives the other portion of the same links, the alternate links

being presented flatwise to the bar and to 10 the pulley whereby the weight of the bar rests on these links, in turn resting on the pulley.

In testimony whereof we hereunto affix our signatures.

FRANK S. INGOLDSBY.
HENRY T. GIBBARD.
